The ornamental design for a manual laundry device, as shown and described.

DESCRIPTION

FIG. 1 is a front perspective view of the manual laundry device according to our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view of the manual laundry device according to our design in a second configuration;

FIG. 9 is a front elevation view thereof;

FIG. 10 is a back elevation view thereof;

FIG. 11 is a right side elevation view thereof;

FIG. 12 is a left side elevation view thereof;

FIG. 13 is a top plan view thereof; and,

FIG. 14 is a bottom plan view thereof.

Broken lines depicting portions of the manual laundry device form no part of the claimed design.

1 Claim, 14 Drawing Sheets(56)
